UNITED STATES PATENT OFFICE.

CHARLES L. BALDWIN, OF WATERLOO, IOWA.

CONCRETE-MIXER.

No. 853,945.

Specification of Letters Patent.

Patented May 21, 1907.

Application filed January 15, 1906. Serial No. 296,034.

To all whom it may concern:

Be it known that I, CHARLES L. BALDWIN, a citizen of the United States of America, and a resident of Waterloo, Blackhawk county, 5 Iowa, have invented certain new and useful Improvements in Concrete-Mixers, of which the following is a specification.

My invention relates to concrete-mixers, and the object of my improvement is to provide such a form of mixing-drum with obliquely set shears therein as will, when rotated, most thoroughly agitate and mix the contents. This object I have effected by the mechanism which is hereinafter described 15 and claimed, and which is illustrated in the drawings hereto annexed, in which—

Figure 1 is a side elevation of my improved concrete-mixer, Fig. 2 is an end elevation of same, Fig. 3 is a vertical axial section of the 20 mixing-drum, showing one side of the interior, Fig. 4 is also a vertical axial section of the said mixing-drum, showing the other side of the interior, while Fig. 5 and Fig. 6 are side elevations of mixing-drums having 25 other specific and varied forms.

Similar numbers refer to similar parts throughout the several views.

My improved mixing-drum has its receiving spout 8 and delivery spout 7 respectively 30 furnished with journals set between the flanges 9 and these journals are supported and revolve within the bearings 10, 11, attached to a tilting hanging frame 27 supported by hangers 14 and 15 from the stub-shafts 16 and 17, respectively. The hanger 14 is fixedly connected to the stub-shaft 16, while the hanger 15 is rotatably mounted on the stub-shaft 17. The stub-shaft 16 is rotatably mounted in the bearing 20 on the top 35 of the end post 22, which latter is affixed to one end of a truck-platform 38 mounted on wheels 39. The stub-shaft 17 is rotatably mounted on a bearing 21 on the top of the end post 23 set on the other end of the truck 40 38. A belt-wheel 18 is mounted upon the outer end of the stub-shaft 17, said shaft carrying on its inner end a pinion 43 whose teeth are arranged to intermesh with those of a gear-wheel 40 exteriorly mounted on the 45 ring 1 affixed about the exterior of the mixing-drum concentric with its axis.

From an inspection of Fig. 2 it will be seen that the hangers 14 and 15 are attached to the hanging or tilting frame 27 nearer the receiving end than the delivery end of the mixing drum, or in other words outside of

the center of gravity, so that when the supports 28 and 29 are withdrawn, the delivery end of the tilting frame will drop and permit the contents of the mixing drum to pass out 6c through the spout 7. The delivery end of the tilting frame is supported on the tops of the outer ends of the inwardly bent members 28 and 29 of the levers 31 and 30 respectively. The lever 31 is medially pivoted on the stub 65 bolt 33 set in a bracket 34 extending from the end post 23. The lever 30 is medially pivoted on a stub 32 fixed in a cross-bar 44 attached to the end post 22. The hand-lever 37 is pivoted on the stud extending from the 70 side of the end post 23, the short end of said lever being connected by means of a link 36 with the lower end of the lever 30. A spring 35 is connected between the lever 31 and the post 23. The free end of the lever 31 is also 75 connected to the upper portion of the lever 37 by means of a link 55. The upward movement of the delivery end of the hanging frame 27 beyond the normal is prevented by means of a stop 24 affixed to the post 22. 80 A fixed receiving spout 41 is supported by a curved bracket 42 attached to the hanging frame 27. The inner end of said spout enters and communicates with the interior of the drum through the receiving-cone 8. 85

I have depicted in Figs. 2, 5, and 6 different specific forms of mixing-drums the axis of each being set at an angle of about 45 degrees to the axis of rotation of said drum. Fig. 2 shows the main portion of the mixing-drum to be in the form of a short cylinder capped at either end by truncated cones, having an octagonal plan. The form of mixing-drum shown in Fig. 5 is that of a cylinder having its height equal to its diameter. The 95 form of the drum shown in Fig. 6 is that of a like cylinder having its upper and lower oppositely set edges truncated. Affixed to the interior periphery of the mixing-drum shown in Figs. 3 and 4, are inwardly extending 100 transverse bars numbered from 47 to 54, inclusive. These shears are set only on the inner periphery of the cylindrical plate 4, the heads 2 and 6 and the oblique plates 3 and 5 being clear of obstruction. The shears 49 105 and 50 are placed parallel with the formal axis of the drum. The other shears are placed at angles convergent to or divergent from each other as shown in Figs. 3 and 4. In case mixing-drums of the forms shown in Figs. 5 and 6 are used, the shears 47 to 54, inclusive, are placed along the inner periph-

eries of said drums attached to the cylindrical plates in the same manner as the shears are attached to the cylindrical plate 4 shown in Fig. 3.

- 5 When the mixing-drum is rotated by means of the belt-wheel 18 and gearing 40, 43 as shown, the materials in said drum are, by reason of the peculiar shape of the drum, collected and then thrown across the drum 10 twice during each revolution. The shears 47 to 54, inclusive, by means of their constant change of position relative to the axis of rotation of the drum, constantly catch up and agitate the materials therein causing them to 15 be thrown in every conceivable direction, causing in the briefest time an adequate amalgamation. As usual in this class of machinery, the unmixed materials are introduced through the receiving spout 41 into 20 the mixing-drum, whence, after admixture, the commingled mass is evacuated from the mixing-drum in the following manner. The upper part of the hand-lever 37 being moved outward, the levers 30 and 31 linked thereto 25 have their upper members 29, and 28, respectively, withdrawn from beneath the hanging frame 27, permitting the mixing-drum to tilt sufficiently to permit its contents to flow out through the spout 7. When 30 emptied the mixing-drum may be brought back to its former position by means of the hand-lever 19.

Having described my invention, what I claim as new and desire to secure by Letters 35 Patent, is—

1. In a concrete mixer, the combination of a revoluble mixing drum comprising a hollow cylinder with closed truncated conical ends, the axis of said drum being inclined 40 to the axis of rotation, an inlet spout and an outlet spout connected to opposite ends of said drum in the axis of rotation, a tilting frame, and bearings on said tilting frame for rotatably supporting said spouts.
- 45 2. In a concrete mixer, the combination of a revoluble mixing drum, comprising a hollow cylinder having closed truncated conical ends the axis of said drum being inclined to the axis of rotation, an inlet spout and an outlet spout connected to opposite ends of said drum in the axis of rotation, a tilting frame, bearings thereon for said drum, and trunnions on the tilting frame outside the center of gravity of said frame and mixing 50 drum.
- 55 3. In a concrete mixer, the combination of revoluble mixing drum, comprising a hollow cylinder having closed truncated conical ends, the axis of said drum being inclined to

the axis of rotation, an inlet spout and an 60 outlet spout connected to opposite ends of said drum in the axis of rotation, a tilting frame rotatably supporting said drum, trunnions on the tilting frame outside the center of gravity of said tilting frame and mixing 65 drum, means for holding the tilting frame in operative position, and means for rotating said drum.

4. In a concrete mixer, the combination of a revoluble mixing drum, comprising a 70 hollow cylinder having closed truncated conical ends the axis of said drum being inclined to the axis of rotation, an inlet spout, and an outlet spout connected to said drum, the said spouts being in the axis of rotation. 75

5. In a concrete mixer, the combination of a revoluble mixing drum comprising a hollow cylinder having closed truncated conical ends, the axis of said drum being inclined to the axis of rotation, an inlet spout and an 80 outlet spout connected to opposite ends of said drum, the said spouts being in the axis of rotation, and shears within said drum arranged partly in parallel relation and partly at divergent angles to each other. 85

6. In a concrete mixer, a tilting frame provided with trunnions outside its center of gravity, a revoluble mixing drum comprising a hollow cylinder having closed truncated conical ends the axis of said drum being inclined to the axis of rotation, an inlet spout and an outlet spout connected to said drum in the axis of rotation, bearings on said tilting frame rotatably supporting said spouts, means for detachably holding said tilting frame in operative position, a gear ring surrounding said drum, and means for turning said gear ring to cause the rotation of the drum. 95

7. In a concrete mixer, the combination 100 of a revoluble mixing drum having its axis of figure inclined to its axis of rotation, an inlet spout and an outlet spout connected to opposite ends of said drum in the axis of rotation, a tilting frame having bearings for 105 the ends of said spouts, trunnions on said tilting frame outside the center of gravity of said tilting frame and mixing drum, a frame provided with bearings for said trunnions, and means mounted on said latter 110 frame for detachably holding said drum with its axis of rotation in a horizontal line.

Signed at Waterloo, Iowa, this 26th day of Dec., 1905.

CHARLES L. BALDWIN.
